UNITED STATES PATENT OFFICE.

EDWARD DANIEL MEIER, OF ST. LOUIS, MISSOURI.

FURNACE-TILING.

SPECIFICATION forming part of Letters Patent No. 651,467, dated June 12, 1900.

Application filed September 25, 1899. Serial No. 731,641. (No model.)

To all whom it may concern:

Be it known that I, EDWARD DANIEL MEIER, a citizen of the United States, residing at the city of St. Louis, in the State of Missouri, have 5 invented a certain new and useful Improvement in Furnace-Tiling, of which the following is a full, clear, and exact description, such as will enable others skilled in the art to which it appertains to make and use the same, reference being had to the accompanying drawings, forming a part of this specification, in which—

Figure 1 is a top plan view of a portion of two tubes, showing two of my improved tiles 15 in position thereon, one of said tiles being shown in horizontal position, and a third in an entering position. Fig. 2 is a cross-sectional view through the tubes, showing one of the tiles in position in full lines and in 20 dotted lines a tile between the tubes in its entering position. Fig. 3 is a similar view showing a solid tile or one not provided with central openings. Figs. 4, 5, and 6 are longitudinal sectional views of several forms of 25 tiles, showing how the same interlock with each other, so that each tile may be supported when broken in whole or in part by its neighbor.

This invention relates to a new and useful 30 improvement in furnace-tiles designed particularly for use in connection with water-tube boilers, wherein the tiles are arranged on the tubes in such manner as to form diaphragms or curtain-walls for giving a direction 35 to the escaping products of combustion, so that said products of combustion will traverse the tubes to the best advantage.

The objects of the invention are to provide 40 tiling of the character described composed of separate pieces designed to be individually introduced or removed from their position between the tubes, so that the water-tubes and the tiling supported thereby may expand and contract independently, and should one or 45 more of said tiles in a longitudinal series be broken the other tiles of that series may be moved longitudinally of the tubes to fill up the gaps at the end of the series to make the line of the desired length.

50 With these objects in view the invention consists of a furnace-tile provided with recesses in its side edges to receive and coöp-

erate with two adjacent tubes, the thickness of said tile being less than the distance between said tubes, whereby said tile may be 55 introduced edgewise between the tubes and turned substantially at right angles to its entering position to engage the tubes, and thus be supported in position by the tubes.

Another feature of the invention consists 60 in rounding the edges of the tube-recesses, so that the tile is permitted to be turned into position to engage the tubes and when so turned will practically fill the entire space 65 between the tubes.

Another feature of the invention resides in the provision of an air-space formed in the body of the tile, the air-spaces of a longitudinal series of tiles registering with each other to form an uninterrupted opening which 70 serves to retain the heated air therein and also permits the introduction of a rod, which serves as a key to lock all of the tiles of a longitudinal series in position on the tubes, so that they cannot be rotated out of their 75 designed position.

In the drawings, A represents a portion of two tubes, which are substantially parallel, and in a subhorizontal water-tube boiler are arranged to form straight series, the tubes of 80 each series being staggered with relation to the tubes of each series thereabove or therebelow.

My improved form of tile is adapted to co-operate with one or more of such horizontal 85 series of tubes to form a diaphragm or diaphragms by filling the spaces between said series of tubes—say at one end thereof—to prevent the products of combustion from passing between the tubes at the place occupied by the tiling.

My improved tiling may be made of fire-clay or asbestos-board, or a mixture of the two, or any suitable refractory material. The tiling consists of separate bricks or tiles B, 95 having a body portion whose thickness is somewhat less than the space between two tubes. The upper and lower faces of these tiles may be straight or curved, as shown in Figs. 2 and 3. The side edges are formed with recesses, preferably semicircular in shape and having a diameter slightly in excess of the diameter of the tubes with which they coöperate. The edges of these recesses are round,

as at b' , in order that the tile may be introduced and turned in either direction to engage the tubes and when in position to fully occupy the space between two tubes. It is 5 obvious, however, that instead of both corners of the semicircular opening being round diametrically-opposite corners of each recess could be round, leaving square shoulders at the remaining corners; but this would necessitate the introduction of the tile into position or removing it from position by turning it in one direction only. I prefer to form an opening b'' through the body portion of each tile for the purpose of lightening the same 10 and also observing, as near as possible, a uniform cross-section through the tile at various points, so that when the tiles are made of fire-clay and baked in a kiln they will burn uniformly and not be distorted or warped 15 out of position by reason of uneven distribution of material. This opening also serves as a chamber for containing heated air for preventing the tiles and their surrounded tubes from being chilled when the furnace- 20 door is open, as in the act of firing, and may be used for introducing and heating a current of air to complete or intensify the combustion of the gases.

As shown in Fig. 2, a rod C may be introduced through the aligned openings of a series 25 of tiles, so as to clamp them together against longitudinal and rotary displacement.

In placing a tile in position it is introduced from above or below into the space between 30 two tubes and turned at right angles until its side recesses receive the tubes, after which it is slid longitudinally on the tubes to its designed position. Another tile is similarly introduced and slid longitudinally the tubes until 35 its front or back face engages with its companion, the space between two tubes being built up to the desired length by introducing tiles separately and sliding them to their designed position until they form a compact line. The tiles are similarly introduced into 40 the next space between two tubes, and so on, clear across the series of tubes, forming when in position a compact diaphragm for giving a definite direction to the products of combustion and also a protecting-covering for the tubes. The side edges of each tile above and 45 below the tubes preferably terminate approximately at a vertical line drawn through the center of the tube; but it is obvious that these lateral projections from the body of the tile can be shortened, so that the side faces thereof will be located some distance to one side of the centers of the tubes, the projections being just long enough to firmly support the 50 tiles in position and cover the greater portion of the exposed lower surfaces of the tubes.

In Fig. 4 I have shown a tile in which the upper and lower portions are offset with relation to each other, forming shoulders d and 55 e on the front and back faces thereof, respectively. These shoulders on the different tiles co-operate with each other when the tiles are

placed close together, all of the shoulders e resting upon the shoulders d , so that each tile supports and is supported by its neighbor. 70 This is advantageous in cases where one of the tiles is broken or burned off in part, said burned or broken tile being supported in position by its adjacent companion. Where these shoulders are used, the rod C may be 75 dispensed with.

In Fig. 5 I have shown a projection F formed on one face of each tile, which is designed to be received in a seat or corresponding depression G in the face of a companion tile, so that when said tiles are placed in position one supports the other by means of these projections. These projections may be in the form of bosses and circular depressions 80 or transverse ribs and straight seats. 85

In Fig. 6 the tiles are shown bent as an entirety, the projecting face fitting into the depression in the next adjacent tile. In all forms shown the object generally is to support the broken portion of any tile by its 90 neighbor, so that the cost of repairs is reduced to a minimum, the tiles, although broken or burned, lasting until a great number are destroyed.

I am aware that there are minor changes in 95 the arrangement, construction, and combination of several parts of my device which can be made and substituted for those herein shown and described without in the least departing from the nature and principle of my 100 invention.

Having thus described my invention, what I claim, and desire to secure by Letters Patent, is—

1. The herein-described tile for boiler-furnaces comprising a body portion and a lateral projection on each of its two opposite ends for engagement with the furnace-tubes, the body portion being of such width and length relative to distance between the tubes 105 that the tile can be introduced edgewise between the tubes and then turned to bring the projections into engagement with the tubes, substantially as described.

2. The herein-described tile for boiler-furnaces comprising a body portion having recesses in its opposite ends for receiving the furnace-tubes, the walls of said recesses being rounded and the tile being of such width relative to the distance between the furnace-tubes that the tile can be introduced edgewise between the tubes and then turned to bring the walls of the recesses into engagement with the tubes, substantially as described. 115 120 125

3. The combination with two water-tubes, of a tile comprising a body portion formed with recesses in its side edges for receiving said tubes, the thickness of said body portion of the tile being less than the distance between said two tubes, whereby said tile may be introduced edgewise between two tubes and turned into engagement with the tubes; substantially as described. 130

4. The combination with two tubes, of a tile comprising a body portion whose thickness is less than the distance between said tubes, said body portion having recesses in its side edges to receive the tubes, the edges of said recesses being rounded; substantially as described.

5. The herein-described tile for boiler-furnaces comprising a body portion and a lateral projection on each of its two opposite ends for engagement with the furnace-tubes, the body portion being of such width and length relative to distance between the tubes that the tile can be introduced edgewise between the tubes and then turned to bring the projections into engagement with the tubes, said tile being formed with a hole through its body portion, substantially as described.

6. The combination with two tubes, of a series of tiles whose body portions are provided with aligned openings, the side edges of said tiles being recessed to engage the tubes, and a rod C passing through the openings in

the body portion of the tile; substantially as described.

7. The herein-described tile for boiler-furnaces comprising a body portion formed of projections and recesses on opposite faces respectively, so as to support, and be supported by, its companion; substantially as described.

8. The combination with two water-tubes, of a tile comprising a body portion formed with lateral projections designed to coöperate with the tubes to support the tile in position, and projections and recesses formed on and in opposite faces of the tile respectively, whereby said tile supports, and is supported by, its companions; substantially as described.

In testimony whereof I hereunto affix my signature, in the presence of two witnesses, this 9th day of September, 1899.

EDWARD DANIEL MEIER.
